UNITED STATES PATENT OFFICE

115,572

DESIGN FOR A STUFFED ANIMAL TOY

Leo L. Weiss, New York, N. Y.

Application April 25, 1939, Serial No. 84,547

Term of patent 7 years

To all whom it may concern:

Be it known that I, Leo L. Weiss, a citizen of the United States of America, residing at New York city, in the county of New York and State of New York, have invented a new, original, and ornamental Design for a Stuffed Animal Toy, of which the following is a specification, reference being had to the accompanying drawing, forming part thereof.

In the drawing:

Fig. 1 is a front view of a stuffed animal toy showing my new design, and

Fig. 2 is a side view thereof.

The characteristic features of the design are those of the head and face.

I claim:

The ornamental design for a stuffed animal toy, as shown, and described.

LEO L. WEISS.
